UNITED STATES PATENT OFFICE.

BENJIMAN S. MOORE, OF JOLIET, ILLINOIS.

OPERATING MECHANISM FOR DUMPING-BODIES.

1,264,675.

Specification of Letters Patent. Patented Apr. 30, 1918.

Application filed February 1, 1917. Serial No. 145,859.

To all whom it may concern:

Be it known that I, BENJIMAN S. MOORE, a citizen of the United States, residing at Joliet, in the county of Will and State of Illinois, have invented certain new and useful Improvements in Operating Mechanism for Dumping-Bodies, of which the following is a specification.

This invention relates to improvements in dumping trucks and wagons, and more particularly has reference to the mechanism for operating the bodies thereof to effect the dumping of their contents.

The invention contemplates the provision of improved mechanism for the purpose stated whereby the bodies may be moved to dumping position with minimum expenditure of energy by the operator and as readily restored to normal position, the parts being so organized and related as to conform to the varying angles of inclination of the body, and maintain the latter at any angle to which the same may be moved, without derangement of the coöperative relation of the parts.

The invention further has in view the provision of mechanism of the general type indicated designed for compact assembly of its parts, thus requiring but small space for its accommodation when associated with a body, and thereby adapting it particularly for use upon the dumping bodies of motor trucks. It is not, however, restricted to such use but capable of employment on dumping bodies generally, whether applied to self-propelled vehicles or dumping wagons.

Other objects and advantages will appear as the nature of the improvements is better understood, the invention consisting substantially in the novel construction, combination and arrangement of parts hereinafter fully described, illustrated in the accompanying drawings and finally pointed out in the appended claims.

In the drawings—

Figure 1 is a side elevation of a dumping motor truck equipped with the herein described invention.

Fig. 2 is a transverse sectional view of a portion of the truck body and the chassis illustrating the manner of mounting the herein described invention thereon and its relation to the body.

Fig. 3 is a sectional plan view of the structure illustrated in Fig. 2.

Fig. 4 is a longitudinal sectional view of a

portion of the body and chassis, together with the herein described operating mechanism and further illustrating the relation of the latter to the body and chassis.

Fig. 5 is a sectional plan view, on a slightly enlarged scale, taken on the line 5—5, Fig. 4.

Fig. 6 is a detail plan view of the swivel block and the supporting segment therefor in assembled relation.

Figs. 7 and 8 are detail perspective views of the swivel block and supporting segment illustrated in Fig. 6 showing these parts on an enlarged scale.

Referring now in detail to the accompanying drawings, the numeral 10 designates the body of a dumping motor truck, and 11 the chassis thereof. The body 10 is pivotally connected to the chassis 11 at a point adjacent to the rear end of the latter, as at 12, so that the body may be moved to the inclined dumping position illustrated in the dotted lines of Fig. 1. This is in accordance with the usual practice of the art.

Arranged on the under side of the chassis 11, and extending transversely thereof is a support 13, which is preferably in the form of a channel iron, said support being suitably connected to the chassis 11, and projecting upwardly through said support 13 is a shaft 14 at the lower end of which is mounted a worm gear 15 in mesh with a worm pinion 16 carried by a transversely-extending shaft 17 mounted in depending hangers 18 on the support 13. One end of the shaft 17 projects at one side of the chassis 11 and is there provided with an operating handle 19 through the medium of which said shaft 17 is rotated. At the upper end of the shaft 14 is connected a universal joint 20, of approved construction, said joint being also connected to the lower end of a screw-threaded body-actuating shaft 21. It is through the shaft 21 that the body 10 is raised and lowered in the manner herein-after described.

An anti-friction bearing, such as a ball bearing 22, is interposed between the universal joint and the support 13 to facilitate easy movement of the shaft 14. This anti-friction bearing may be of any approved construction.

The body-actuating shaft 21 projects upwardly through a U-shaped notch 23 formed in the forward end of the floor of the body

10, and said shaft 21 engages an internally screw-threaded annular swivel block 24 supported immediately below said opening or notch 23. The block 24 is provided with 5 oppositely-extending trunnions 25, which trunnions are received by bearings 26 formed in a supporting segment 27, and said swivel block 24 is thereby enabled to rock in said bearings 26 under the angular movement of 10 the shaft 21 as it conforms to the varying positions of the body 10 when being moved to dumping position and restored to its normal relation to the chassis 11. Immediately over the segment 27 is a holding plate 28 15 which spans the bearings 26 and the trunnions 25 of the block 24, and said block 24 is thereby held within the supporting segment 27 but capable of being rocked in the manner indicated. Both the segment 27 20 and the holding plate 28 are secured to the bottom of the body 10 at the notch or opening 23 through the medium of bolts 29 or their equivalent.

The actuating shaft 21 fits within and is 25 concealed by an upwardly extending sleeve 30 which is carried by the swivel block 24, and this prevents mutilation and wear of the shaft 21 by its contact with adjacent parts.

30 To maintain the entire structure from contact with the contents of the body 10 a U-shaped guard 31 is provided. This guard extends upwardly from the notch 23 and has attaching flanges 32 at its respective 35 sides, a base flange 33 being also provided and seated upon the bottom of the body 10. This base flange 33 is secured to the bottom by the bolts 29 previously referred to.

A spacing collar 34 held by a set screw 40 35, or its equivalent, is mounted on the shaft 14 between the gear 15 and support 13 to hold the bearing 22 in proper adjustment, and at the same time to lock the shaft 14 against undue vertical movement.

45 As before stated, the herein described mechanism may be applied to dumping motor trucks or ordinary dumping wagons, and with the parts assembled in the manner described it will be apparent that on rotation

50 of the shaft 17 the pinion 16 and gear 15 will impart rotation to the shaft 14. Through the universal joint 20 the body-actuating shaft 21 will also be rotated. As the shaft 21 has threaded engagement with 55 the swivel block 24, the latter being mounted for movement with the body 10, the block 24 will follow the screw-threads of the shaft 21 in accordance with the direction of rotation of the latter. In one direction the

60 block 24 will rise upon the shaft 21, and this movement is effectual to raise the body 10 to the desired angle of inclination for the dumping of its contents. In this movement, however, it will also be seen that the 65 universal joint 20 will permit the shaft 21

to follow the angular movement of the body 10, during which the swivel block 24 is rocked in the bearings 26 on its trunnions 25, so that regardless of the angle of inclination of the body 10 there will be no derangement of the operative relation of the working parts. It is also evident that the body 10 will be held at any position to which it is moved, the screw-threaded engagement of the swivel block 24 with the shaft 21 preventing movement of the body 10 until rotation of said shaft. This will permit the body 10 to be locked at any position.

70 If so desired, the shaft 17 may be suitably connected with the motor, when the mechanism is employed on a motor dumping truck, so that the raising and lowering of the body 10 may be effected by power.

I claim:

1. In mechanism of the class described, 80 the combination with the frame of a vehicle, and a dumping body tiltably mounted thereon, of a vertically-disposed shaft carried by said frame, means for actuating said shaft, a rocking member carried by said body, a 90 screw-threaded actuating member engaged with said rocking member for tilting the body, and a universal joint interposed between said shaft and said screw-threaded actuating member to permit the latter to follow the varying positions of the body when 95 tilted.

2. In mechanism of the class described, 100 the combination with the frame of a vehicle, and a dumping body tiltably mounted thereon, of a vertically-disposed shaft carried by said frame, means at the lower end of said shaft for actuating the same, a universal joint connected to the upper end of said shaft, a screw-threaded actuating member 105 connected to said universal joint, and a follower having a rocking connection with said body and engaged by said actuating member for travel thereon during the operation of said actuating member, whereby to tilt 110 the body and permit the actuating member to conform to the angular position of the body.

3. In mechanism of the class described, 115 the combination with the frame of a vehicle, and a dumping body tiltably mounted thereon, of an actuating shaft operably connected to said body for tilting the same, a universal joint included in said shaft intermediate its ends, means to permit said shaft to conform 120 to the angular position of the body and to preserve its operative relation thereto, and means for operating said actuating member.

4. In mechanism of the class described, 125 the combination with the frame of a vehicle, and a dumping body tiltably mounted thereon, of an actuating shaft operably connected to said body for tilting the latter, a universal joint included in said shaft intermediate its ends, a member having a rocking connection 130

with said body and with which said shaft is connected, and means for operating said shaft.

5. In mechanism of the class described, 5 the combination with the frame of a vehicle, and a dumping body tiltably mounted thereon, of an actuating shaft for tilting said body, a universal joint included in said shaft intermediate its ends, a swivel block 10 having a rocking connection with said body and with which said actuating shaft is connected, and means for operating said actuating shaft.

6. In mechanism of the class described, 15 the combination with the frame of a vehicle, and a dumping body tiltably mounted thereon, the floor of said body having an opening, of a flexibly mounted actuating member for tilting said body, a swivel block 20 arranged at the opening of the body floor and having screw-threaded engagement with said actuating member for travel along the latter when said member is rotated, said block being provided with trunnions, a segment 25 carried by the body and arranged at the opening of the body floor, said segment having bearings into which said trunnions are fitted, whereby said swivel block is adapted to rock in relation to the body during 30 the tilting movements of the latter, and means for operating said actuating member.

7. In mechanism of the class described, the combination with the frame of a vehicle, and a dumping body tiltably mounted 35 thereon, the floor of said body having an opening, of a flexibly mounted screw-threaded shaft for tilting said body, a swivel block arranged at the opening of the body floor 40 and having screw-threaded engagement with said shaft for travel along the latter when said shaft is rotated, said block being provided with oppositely extending trunnions, a supporting segment carried by the body and arranged at the opening of the body 45 floor, said segment having oppositely disposed bearings into which said trunnions are fitted, whereby said swivel block is adapted to rock with respect to said body during the tilting movement of the latter, and means 50 for actuating said shaft.

8. In mechanism of the class described, the combination with the frame of a vehicle, and a dumping body tiltably mounted thereon, of a supporting member extending 55 transversely of said frame, a shaft journaled in said supporting member, means for actuating said shaft, a screw-threaded actuating member rising from said shaft, a universal joint interposed between said shaft and said 60 actuating member to permit said actuating member to tilt with the body, and a member having a rocking connection with said body and also connected to said actuating member

and adapted to travel along the latter, whereby to tilt said body when said actuating member is rotated.

9. In mechanism of the class described, the combination with the frame of a vehicle, and a dumping body tiltably mounted thereon, of a support extending transversely 70 of said frame, a shaft journaled in said support, means for rotating said shaft, a screw-threaded actuating shaft extending upwardly from the first mentioned shaft, a universal joint interposed between said shaft 75 and said actuating shaft, a swivel block associated with said body and having screw-threaded engagement with said actuating shaft, said swivel block being adapted to travel along the actuating shaft when the latter is rotated, whereby to tilt the body, and a support carried by the body and provided with bearings arranged in opposite relation to each other, said swivel block being provided with oppositely extending trunnions seated in said bearings, whereby said block is capable of rocking movement in said bearings with respect to said body during the tilting movement of the latter.

10. In mechanism of the class described, 90 the combination with the frame of a vehicle, and a dumping body tiltably mounted thereon, of a support associated with said frame, a vertically disposed shaft journaled in said support, means for rotating said 95 shaft, a screw-threaded actuating shaft extending upwardly from the first mentioned shaft, a universal joint interposed between said screw-threaded shaft and said first mentioned shaft, a supporting segment carried 100 by the body and provided with oppositely disposed bearings, a swivel block associated with said supporting segment and provided with oppositely disposed trunnions seated in the bearings of said segment, whereby said block is capable of rocking movement with 105 respect to said supporting segment, said block having screw-threaded engagement with said actuating shaft, whereby said block is adapted to travel along said shaft 110 on the rotation of the latter, a holding plate arranged in super-imposed relation to said supporting segment and spanning the bearings of the latter, whereby the swivel block is held within the bearings of said supporting segment, and means for holding said segment and said holding plate in associated 115 relation with said body.

In witness whereof I have hereunto signed my name in the presence of two subscribing 120 witnesses.

BENJIMAN S. MOORE.
